SMOKING PIPE

Filed Sept. 21, 1922

FIG. 1

FIG. 2

FIG. 3

Inventor
JOHN H. SCHRODER

By *A. E. Barker*

Attorney

UNITED STATES PATENT OFFICE.

JOHN H. SCHRODER, OF MINNEAPOLIS, MINNESOTA.

SMOKING PIPE.

Application filed September 21, 1922. Serial No. 589,641.

To all whom it may concern:

Be it known that I, JOHN H. SCHRODER, a citizen of the United States, residing at Minneapolis, in the county of Hennepin and

5 State of Minnesota, have invented certain new and useful Improvements in Smoking Pipes, of which the following is a specification.

This invention relates to tobacco pipes 10 and the main object is to provide a pipe in which, the smoke may be cooled without the use of a long stem, and in which the pipe may be easily cleaned. Further objects will be disclosed in the course of the following 15 specification and are clearly illustrated in the accompanying drawing, wherein:

Fig. 1 is an elevation of the pipe, the greater portion of which is shown in longitudinal vertical section.

20 Fig. 2 is a detail section on the line 2—2 in Fig. 1.

Fig. 3 is a detail view of the spirally grooved cooling piece 19.

Referring to the drawing more particularly and by reference characters, 4 designates the tobacco bowl of a pipe having a stem 5 and a mouth piece 6. The bowl 4 is provided at its lower end with a cylindrical opening 7 in which is frictionally secured 25 a disk 8. A button 9 is loosely slideable in the opening 7 and is provided with a pin 10 which is slidably retained in the disk 8. A spring 11 is interposed between the disk 8 and the button 9 and yieldingly holds the latter 30 in a downward position, as shown. When the button 9 is pushed in with the finger the pin 10 moves up into a hole 12, through which the smoke from 35 the bowl is normally drawn.

40 The stem 5, which is preferably frictionally retained in the bowl, has an aperture 13 at the upper part of its inner end, and at an intermediate point in its bottom is provided with a cleaning port 14. The port 14 is normally closed by the projecting end 45 of a lever 16, which is pivoted as at 17 and has a spring 18 which yieldingly holds the projecting end of the lever in the port opening 14.

50 Within the stem 5 is snugly fitted a cooling piece 19 which is spirally grooved so that the smoke, in passing from the aper-

ture 13 to the mouth piece 6, will not do so in a straight line, as is usual, but will travel a spiral and much longer course, thus giving 55 it time to cool considerably.

The pipe is smoked in the usual manner, the smoke from the burning tobacco passing from the bowl through the passages 12 and 13, and on through the stem and mouth 60 piece to the smoker's mouth.

It frequently happens, in any pipe, that the outlet of the bowl, such as 12, becomes clogged with tobacco so that the smoke passage becomes blocked. When this occurs, in 65 the present construction, it is only necessary to push the button 9 upward. This will poke the pin 10 up into the hole 12 and clear it. When it is desired to clean out the stem 5 and the piece 19 therein, the button 70 9 is again pushed up. As it moves up it not only closes the hole 12 but also opens the port 14 by acting against the inner or short end of the lever 16. Now if the operator blows into the mouth piece 6 he will blow 75 much of the dirt and sediment out through the port 14, as it is the only escape for the air. The pipe can of course be occasionally taken apart for a better cleaning, if and when necessary. 80

It is understood that various modifications may be made in the invention, as above described, provided, however, that such modifications come within the spirit and scope 85 of the appended claims.

Having now therefore fully shown and described my invention, what I claim to be new and desire to protect by Letters Patent is:

1. In a smoking pipe having a bowl and a stem secured at one end therein, said bowl having a smoke outlet and said stem having a normally closed cleaning port, a pin slidably arranged with one end near said outlet for engagement therein, a button on the other end of the pin for actuating the same, and a lever normally closing said port, said lever being actuatable by said button. 90

2. A smoking pipe consisting of a bowl having a smoke outlet, a stem communicating therewith and having a cleaning port, a member normally closing the port, a pin adapted to slidably engage in and close the bowl outlet, means actuated by the pin to 100

operate the port closing member, and a spring for normally holding the pin in a retracted position.

3. A pipe consisting of a bowl having a stem provided with a cleaning port, said bowl having a smoke outlet and a chamber in alignment therewith, a disk arranged in the chamber, a pin slidably arranged in

the disk for closing engagement with the smoke outlet, and means arranged below the disk for yieldingly holding the pin in retracted position with respect to the outlet.

In testimony whereof I affix my signature.

JOHN H. SCHRODER.
